UNITED STATES PATENT OFFICE.

EUGEN HURWITZ, OF BERLIN, GERMANY, ASSIGNOR TO GENERAL ELECTRIC COMPANY, A CORPORATION OF NEW YORK.

APPARATUS FOR DRAWING WIRES.

1,023,316.

Specification of Letters Patent. Patented Apr. 16, 1912.

Application filed January 19, 1912. Serial No. 672,196.

To all whom it may concern:

Be it known that I, EUGEN HURWITZ, a subject of the Emperor of Germany, residing at Berlin, Germany, have invented certain new and useful Improvements in Apparatus for Drawing Wires, of which the following is a specification.

My invention relates to drawing wires from metals such as tungsten which should be heated during the drawing operation in order to increase the ductility. For this purpose, the wire may be heated either by a flame or by passing an electric current through the portion of the wire just entering the die.

The object of my invention is to insure that the wire is properly heated but not overheated even though the speed of drawing may be varied considerably.

My invention consists in providing means for automatically varying the heat energy supplied to the wire upon a variation of the speed with which the wire is drawn through the die. Thus the faster the wire is drawn, the more heat is supplied to the wire, so as to bring it to the proper temperature by the time it reaches the die.

The accompanying drawing shows diagrammatically one suitable arrangement of apparatus for carrying out my invention.

If the wire is heated by means of an electric current the temperature may easily be adapted to the particular thickness of wire, the particular speeds of drawing, the properties of the material, etc., and by calculation it may be determined how many amperes should be sent through how great a length of wire of a certain thickness when drawn at a given speed, in order to obtain the proper temperature at the die. The temperature of the wire at the die may be regulated both by varying the amount of current supplied to the wire, and by varying the length of the wire to which the current

is supplied by shifting one terminal of the current supply toward or away from the die. When metallic dies are used the second terminal of the current supply may be formed by the die itself. If non-conducting bodies are employed as dies, such as sapphires, diamonds, etc., then the second current conductor is placed just beyond the die. In the latter case since the end of the wire that has been drawn through the die is smaller than the one which has not yet been drawn

through and since with the same current intensity the smaller end reaches a higher temperature than the coarser end which has not been drawn, it is desirable to make provision for cooling the smaller end. This may be done, for example, by directing a current of air or other gas against the piece of wire as it comes out from the die. The current conductors may, with coarser wires, be formed by metallic brushes, while with smaller wires metallic drums may be employed about which the wire is carried one or more times. Metals which tend strongly to oxidation may be protected from the access of air by being carried through a tube or casing during the heating operation, which tube or casing is filled with an inert gas.

In the accompanying drawing which shows diagrammatically one suitable arrangement, A represents the wire, and B the die.

C, C', represent reels on, and from which, respectively, the wire is being wound.

D represents diagrammatically the armature of a small electric motor driving the reel C. The motor D is represented as a shunt motor, its field winding being indicated at d.

F represents a field rheostat for regulating the speed of the motor.

E represents the source of the current supply.

g, g' represent brushes or other suitable means for conveying current to and from the wire A. If the die B is of steel the brush g' may be omitted and the die itself constitute the second terminal. A rheostat H is placed in circuit with the wire and is connected to the field rheostat F, so that when the field rheostat is moved to vary the speed of the motor the rheostat H is moved to increase the current through the wire for higher speeds and to decrease it for lower speeds.

h represents a permanent resistance in the circuit of the wire. If the wire is readily oxidizable, the heated portion entering the die may be inclosed in a suitable casing J connected to a source of inert gas through a pipe j. The pressure in this casing may be slightly above atmospheric pressure so that whatever leakage occurs through the casing will be outward. If non-conducting dies are used so that the brush g' is employed the wire leaving the die may be cooled by a

blast of air or inert gas issuing from the nozzle K which is connected by a pipe k to a suitable source of pressure.

I do not desire to limit myself to the particular construction and arrangement of parts shown and described, but aim in the appended claims to cover all modifications which are within the scope of my invention.

What I claim as new and desire to secure 10 by Letters Patent of the United States, is—

1. In an apparatus for drawing wire, in combination with the drawing die, driving means for drawing the wire through the die, means for heating the wire immediately 15 before its passage through the die, means for varying the speed of the driving means, and means for automatically varying the heat energy supplied to the wire upon a variation of the speed of the driving means.

2. In an apparatus for drawing wire, in combination with the drawing die, driving means for drawing the wire through the die, means for supplying electric current to the portion of the wire just entering the die

to heat it, means for varying the speed of 25 the driving means, and means for automatically varying the current supplied to the wire upon a variation of the speed of the driving means.

3. In an apparatus for drawing wire, in 30 combination with the drawing die, electrically operated driving means for drawing the wire through the die, means for supplying current to the portion of the wire just entering the die to heat it, switch contacts 35 for varying the speed of the driving means, switch contacts for varying the amount of current supplied to the wire, and operative connections between the two sets of switch contacts for insuring their simultaneous operation.

In witness whereof, I have hereunto set my hand this 4th day of January, 1912.

EUGEN HURWITZ.
